UNITED STATES PATENT OFFICE

121,680

DESIGN FOR A BRASSIÈRE OR SIMILAR ARTICLE

Seymour Katz, Chicago, Ill., assignor to Philip S. Bloom Co., Chicago, Ill., a corporation of Illinois

Application April 1, 1940, Serial No. 91,376

Term of patent 7 years

To all whom it may concern:

Be it known that I, Seymour Katz, a citizen of the United States, residing at Chicago, in the county of Cook and State of Illinois, have invented a new, original, and ornamental Design for a Brassière or Similar Article, of which the following is a specification, reference being had to the accompanying drawing forming part thereof.

Fig. 1 is a perspective view of a brassière or similar article embodying my new design; and

Fig. 2 is a profile section thereof, taken on the line 2—2 of Fig. 1.

The dominant feature of the design is disclosed in solid lines in Fig. 1; the shoulder straps and back strap are indicated in dotted lines.

The back of the brassière is conventionally plain.

I claim:

The ornamental design for a brassière or similar article, as shown and described.

SEYMOUR KATZ.
